5 Claims. (Cl. 178—7.6)

This invention relates to scanning mechanism and more particularly to electromagnetic means for oscillating a pivotally mounted mirror.

In television scanning systems, oscillographs, and the like, it is often necessary to periodically produce an angular deviation of a mirror in response to electrical impulses. The results are often times obtained through the use of a magnetically permeable armature connected to an oscillatable mirror, or through the use of a properly designed rotating cam and follower mechanism suitably connected to the mirror.

Moving armatures oscillated by the intermittent electrical impulses have the disadvantage of having relatively great weight and the attendant disadvantage of being unable to respond to high frequency electrical impulses because of the inertia of the moving parts. Cams have proven satisfactory as a driving medium but they are subject to the disadvantage that they are relatively expensive to fabricate and the motion produced is limited strictly by the design of the cam. Furthermore, such cams are exposed to wear, they must be rotated at constant speed, and they operate with relatively high inertia.

In the present invention it is proposed to utilize the flexibility of the electrical wave-form to obtain any desired mechanical wave form.

The objects, therefore, of the present invention are: to provide an improved scanning mechanism operable by electrical impulses; to provide in such a mechanism mirror-oscillating means having a minimum inertia to motion; to provide in such mechanism means comprising a moving coil for reaction with the electrical impulses; to provide improved means for flexibly connecting the moving coil with the mirror; and to provide means for minimizing chattering of the device at operating frequencies. These and other objects will become more readily apparent from the following description in conjunction with the appended drawings showing one form of scanning mechanism incorporating the present invention.

In the drawings:

Fig. 1 is a vertical sectional view taken through the improved scanning mechanism;

Fig. 2 is a sectional view taken on the line 2—2 of Fig. 1;

Fig. 3 is a detail sectional view taken on the line 3—3 of Fig. 2; and

Fig. 4 is a view of a modified form of mirror connecting means.

Briefly, the invention comprises a magnet and coil construction of a type similar to that employed with dynamic loudspeakers. A magnet

M generates magnetic lines of force across an air gap, preferably of annular shape, and a moving coil C assembly corresponding in design with the voice coil of a dynamic loudspeaker is located within the annular gap so as to intercept the magnetic lines of force. A connecting link L extends from the moving coil assembly to a pivotally mounted mirror assembly P in such a way that movement of the coil imparts an angular motion to the mirror about the axis of the pivotal mounting.

Referring now in greater detail to the drawings, the magnet M comprises a permanently magnetized core structure 11 of steel, nickel-iron alloy or other suitable material having high permeability and remanence. The core structure 11, as shown in the drawing, comprises an annular shell 12 having a centrally located pole-piece 13 mounted to a bridging top plate 14. An annular base plate 15 is secured to the shell 12 so as to complete the magnetic path with the bottom of the pole-piece 13 through an intermediate air-gap 16 preferably of annular shape. The base plate 15 is relatively thick and its central aperture is dimensioned so as to be but slightly larger than the diameter of the pole-piece 13 so that the annular magnetic path formed comprises a deep space with but a narrow gap between the adjoining parts so as to provide an intense radial magnetic field in the air gap. A tubular dome 17 of non-magnetic material such as cardboard, fiber, or the like extends within the air-gap closely about the pole-piece 13 and is provided with a winding of small insulated wire about its outer periphery, the terminals 19 of which extend downwardly from the dome 17 for connection with a source of electrical impulses. The dome 17 is supported by a diaphragm 21 of paper or the like preferably provided with a series of annular corrugations, which diaphragm 21 permits the coil to move in an axial direction but inhibits its motion transversely. The diaphragm 21 is secured directly against the base plate 15 by means of a clamping ring 22. The movable coil C comprising the dome 17 and the winding 18 is joined with the pivotally mounted mirror P by means of the connecting link L comprising a stem 23 secured at the base of the dome 17 by means of a machine screw 24 and reinforcing washers 25. The stem is slidably mounted within a bushing 26 disposed axially about the stem in spaced relation to the dome 17. The bushing is firmly secured within a support 27 extending from the base plate 15.

The pivotally mounted mirror P comprises a

sheet of reflecting material such as polished metal, silvered glass, or the like firmly secured to a spindle 30, having axially located sockets 31 at the respective extremities thereof. A pair of 5 pivot mounting blocks 32 are secured to a base member 33 as by screws 34. Pivots 35 preferably comprising threaded rods having hardened conical points 36 extend through the blocks 32 into the respective sockets 31 at each end of the spindle 30. The pivots 35 are adjusted until the spindle pivots freely without lost motion, at which time locknuts 37 are tightened to hold the pivots in the adjusted position. A radius arm or pivoting link 38 is tightly secured to the spindle 30 as 10 by means of a locking screw 39. The radius arm 38 connects with the stem 23 through a resilient link 41 preferably comprising a thin strip of tempered spring steel secured in any convenient manner at its opposite ends to the stem 23 and 15 the arm 38. The magnet M is supported in fixed relation to the base member 33 by a plurality of legs 42.

The device operates as a scanning mechanism by projecting a beam of light upon the pivotally 20 mounted mirror P and attaching the terminals 19 to the source of electrical impulses. Presuming for example that the electrical impulses comprise intermittent surges of electric current as an alternating current sine-wave, the current passing 25 through the winding 18 exerts alternating impulses in the highly concentrated magnetic field in the air-gap 16 with the effect that the movable coil C is subjected to an oscillating motion along the axis of the stem 23. This motion is 30 imparted through a resilient link 41 to the radius arm 38 causing the pivotally mounted mirror P to oscillate angularly, thus imparting the desired scanning motion to the reflected light beam. With an exciting impulse of sine-wave shape, the 35 mirror is oscillated substantially according to simple harmonic motion. As the arm 38 pivots from the horizontal position shown in Fig. 1 its lateral distance from the stem 23 decreases. This motion is of such small magnitude, however, that 40 it is compensated for by flexing of the link 41. At the same time the tendency for the flexible link to return to a straight position maintains the parts under a slight tension and operates to minimize chattering when the device is in operation.

In Fig. 4 a slight modification of the connecting link L is shown. Instead of the resilient link 41 use is made of a flexible cable, cord, or chain 43 which is operative to lift the radius arm 38 whenever the stem 23 is raised, and a helical tension spring 44 is secured to the arm 38 so as to return the arm to the lower position whenever such motion is permitted by a corresponding lowering of the stem 23. With the modified arrangement there is less tendency for a sideways force to be exerted against the stem 23 as might be exercised by a resilient link 41, which pressure may increase the friction between the stem 23 and the bushing 26 if the angular motion is excessive.

It will be noted that the magnetic forces of the moving parts are obtained without the use of an iron armature or its equivalent, and the weight of the moving parts has been maintained at a minimum. The repulsion and attraction is 65 obtained through the use of a light-weight moving coil which provides for accurate response even at comparatively high frequencies of the electrical impulses, as the moving parts do not possess the high inertia of an iron armature. Furthermore, the elimination of iron from the 70

moving parts eliminates hysteresis as a factor limiting the frequency of operation. Since the design incorporates features of the dynamic loud-speaker the limiting operating frequency may be estimated roughly as the highest pitch note to which such type of speaker responds, as the inertia of the oscillating mirror and the connecting link does not differ materially from the mechanical inertia of the usual paper cone. A dynamic speaker may be converted to use in the improved 10 scanner by removing the cone from the unit, and by suitably connecting the mirror to the moving coil assembly.

In practice we have found that at all ordinary television frame-scanning frequencies, this device 15 readily reproduces mechanically the wave-form of the exciting current, irrespective of its shape. For example double, and even single sawtooth wave-forms are faithfully reproduced.

It will be appreciated, of course, that while a 20 magnet of the permanently magnetized type has been shown, electromagnetic units for generating the annular flux field may be employed equally well.

The corrugated diaphragm 21 herein described 25 exerts a steady influence on the motion of the coil assembly. The inertia of this diaphragm may be lessened by forming lightening holes therein, or the diaphragm may be formed as a spider having radial supporting arms similar to 30 the support 27. In some cases the diaphragm may be eliminated entirely, rendering the device more sensitive at high frequencies.

Obviously, the connection between the mirror and the moving coil may be of any suitable design. The dome disclosed is desirable in that it provides a rigid connection having light weight.

Various other changes will suggest themselves to one skilled in the art without departing from the scope of the invention or sacrificing any of 40 its advantages.

We claim:

1. In combination a dynamic unit having a coil movable in an annular magnetic field and responsive to electrical impulses, a member connected for movement axially with said coil, a pivotally movable scanning mirror, and means connecting the said member and mirror to oscillate the latter and compensating for the arcuate movement of the mirror in translating the linear movement to oscillating motion.

2. In combination a dynamic unit having a coil movable in an annular magnetic field and responsive to electrical impulses, a member connected for movement axially with said coil, a pivotally movable scanning mirror, and flexible means connecting the said member and mirror to oscillate the latter and compensating for the arcuate movement of the mirror in translating the linear movement to oscillating motion.

3. In combination a dynamic unit having a coil movable in an annular magnetic field and responsive to electrical impulses, a member connected for movement axially with said coil, a pivotally movable scanning mirror, and resilient means connecting the said member and mirror to oscillate the latter and compensating for the arcuate movement of the mirror in translating the linear movement to oscillating motion.

4. In combination a dynamic unit having a 70 coil movable in an annular magnetic field and responsive to electrical impulses, a member connected for movement axially with said coil, a pivotally movable scanning mirror, and leaf spring means connecting the said member and 75

mirror to oscillate the latter and compensating for the arcuate movement of the mirror in translating the linear movement to oscillating motion.

5. In combination a dynamic unit having a coil movable in an annular magnetic field and responsive to electrical impulses, a member connected for movement axially with said coil, a

pivottally movable scanning mirror, and means connecting the said member and mirror to oscillate the latter and compensating for the arcuate movement of the mirror in translating the linear movement to oscillating motion and tension means assisting the oscillatory movement. 5
